M. NIGRO

ARMOR OR TUBE FORMING MACHINE

Original Filed July 3, 1925

UNITED STATES PATENT OFFICE.

MICHEL NIGRO, OF WORCESTER, MASSACHUSETTS, ASSIGNOR TO SLEEPER & HARTLEY, INC., OF WORCESTER, MASSACHUSETTS, A CORPORATION OF MASSACHUSETTS.

ARMOR OR TUBE FORMING MACHINE.

Application filed July 3, 1925, Serial No. 41,323. Renewed September 24, 1928.

My invention relates to armor or tube forming machines and has for its object to provide an improved machine of the class described which is particularly adapted for the 5 production of flexible metallic armor or tubular casing from flat stock, that is, stock which is substantially rectangular in cross section.

In the copending application of Frank H. Sleeper, Serial No. 28,709, filed May 7, 1925, 10 and assigned to Sleeper & Hartley, Inc., there is shown and described an armor or tube forming machine comprising a rotatable flier carrying feeding and forming rolls which are positively driven so as to form and feed the flat 15 stock, at a predetermined rate, to coiling devices also rotatable with the flier, whereby tubular casing is formed as the flier rotates. The present invention relates to machines of 20 the type described in the above mentioned copending application, and has for its object to provide an improved mounting for the feeding and forming rolls, whereby the rolls may be quickly and conveniently adjusted to control the pitch of the tubing formed by the 25 rotation of the flier.

In the accompanying drawings.

Fig. 1 is a view in front elevation of the machine embodying my invention;

Fig. 2 is a horizontal sectional view along the line 2—2 of Fig. 1, looking in the direction of the arrows; and

Fig. 3 is an enlarged fragmentary view illustrating details of the improved mounting of the feeding and forming rolls.

Like reference characters refer to like parts in the different figures.

Referring to Figs. 1 and 2, the machine comprises a pedestal or base 1 having an upwardly extending portion 2 through which extends a hollow sleeve 3 rotatably supported near its ends in anti-friction bearings 4. The sleeve 3 is provided at one end with a radial web 5 surrounded by an integral concentric flange 6, which is adapted to receive a belt 7 for rotatably driving, from any suitable source of power, the sleeve 3, together with the stock reel and stock feeding and coiling devices, the whole constituting what will be hereinafter termed the flier.

As fully shown and described in the above mentioned copending application, an annular bundle of flat stock 8 is supported on a rim 9 concentric about the axis of rotation of the sleeve 3, the rim 9 being so mounted as to permit the stock 8 to be drawn off as the entire

stock supply rotates with the flier. The stock 8 is led from the supply reel over guide rolls 10 to a pair of stock forming and feeding rolls 11, the mounting of which forms the subject matter of the present application, as will now be described.

As best shown in Figs. 2 and 3, the rolls 11 are carried by a bracket 12 which is provided with ears 13, 13, pivotally connected to lugs 14, 14, projecting from the web 5 by pins 15, 15. The opposite end of the bracket 12 is provided with an opening for receiving a stud 16, having an eye portion which is pivotally connected to the web 5 by means of a pin 17. Nuts 18 coacting with the stud 16 on opposite sides 70 of the bracket 12 permit the bracket to be adjusted and held in different angular positions with respect to the axis of the pins 15, 15. In other words, the angle which the plane of the bracket 12 makes with the longitudinal axis 75 of rotation of the sleeve 3 may be adjusted to control the pitch of the tube being formed as the strip 8 is fed to the coiling devices by the rolls 11.

As best shown in Fig. 2, the rolls 11 are mounted on shafts 19 which are rotatably supported in bearings 20 carried by the bracket 12 and a plate 21. One of the roll shafts 19 carries a driving gear 22, from which both rolls 11 are adapted to be driven in unison through intermeshing gears 23 also mounted on the shafts 19. The rolls 11 are adapted by their contour to form the stock 8 and, at the same time, to positively feed it at a predetermined rate to the coiling devices, 90 which as best shown in Fig. 1, comprise a group of coiling rolls 24 and coiling tools 25 arranged about the axis of the flier and carried by a plate 26 secured to the web 5. The particular arrangement of the coiling rolls 95 24 and coiling tools 25 forms no part of the present invention, it being sufficient for an understanding of the same to state that when the coiling devices are driven with the flier and the formed strip 8 is positively fed there- 100 to by the rolls 11, a tubular casing is formed, which, as shown in Fig. 2, feeds itself outwardly from the plate 26 as the flier rotates. And it will be evident that the pitch of the tubing being thus formed will be positively 105 determined by the angle which the bracket 12 makes with the axis of rotation of the flier.

As shown and described in the above mentioned copending application, the power for driving the rolls 11 is derived from a hollow 110

sleeve 27 which extends longitudinally through the flier sleeve 3 and is rotatably supported therein by anti-friction bearings 28 and 29 carried by the sleeve 3 and by an end plate 30, respectively. The gear 22 on the roll shaft 19 is in mesh with a gear 31 carried at one end of the inner sleeve 27, while the other end of the sleeve 27 carries a gear 32. The sleeve 27 is adapted to be driven from a countershaft 33 through change gears 34 and 35, as shown in the above mentioned copending application, or in any other suitable manner.

From the foregoing it is apparent that by 15 my invention I have provided an improved mounting for the positively driven feeding and forming rolls of a tube forming machine, whereby the plane of rotation of the rolls may be quickly and conveniently adjusted to control the pitch of the tubing formed by the rotation of the flier.

I claim:

1. In a machine of the class described, the combination with a rotatable member carrying a supply of strip material, positively driven strip feeding rolls carried by said rotatable member, and coiling devices carried by said member adapted to form said strip into a tube, of means for adjusting said rolls to vary the pitch of the tube being formed.

2. In a machine of the class described, the

combination with a rotatable member carrying a supply of strip material, positively driven strip feeding rolls carried by said rotatable member, and coiling devices carried by said member adapted to form said strip into a tube, of means for adjusting said rolls to vary the pitch of the tube being formed, said adjusting means being adapted to adjust the plane of revolution of said rolls about an axis extending at right angles to the said tube.

3. In a machine of the class described, a rotatable member carrying a supply of strip material, a bracket carried by said member, positively driven strip feeding rolls carried by said bracket, coiling devices carried by said member adapted to form said strip into a tube, and means to adjust said bracket to vary the pitch angle of the tube being formed.

4. In a machine of the class described, a rotatable member carrying a supply of strip material, a bracket carried by said member, positively driven strip feeding rolls carried by said bracket, coiling devices carried by said member adapted to form said strip into a tube, and means to adjust said bracket about an axis extending at right angles to the axis of the tube to vary the angle of delivery of the strip to said coiling devices as it is formed into a tube.

MICHEL NIGRO.
